UNITED STATES PATENT OFFICE

JOSEF ENGL, OF BERLIN-GRUNEWALD, GERMANY, ASSIGNOR TO ENGL PRODUCTS CORPORATION, OF NEW YORK, N. Y., A CORPORATION OF NEW YORK

SLIT-FORMING DEVICE AND METHOD OF PRODUCING THE SAME

Application filed June 19, 1930, Serial No. 462,200, and in Germany February 11, 1929.

- My invention relates to a member or device which forms or defines a slit or passage to be traversed by a light beam utilizable in various optical systems, such for example, as for recording sound waves on a film or the like or for reproducing sound from such a film; my invention also relates to the method of producing or constructing a member or device of the character stated.
- 10 My invention, in an important phase thereof, relates to a slit-forming device, as aforesaid, of novel design and simple construction and which is operative in a highly efficient manner for the intended purposes.
- 15 Various other objects, advantages and characteristics of my invention will become apparent from the following detailed description taken in connection with the accompanying drawing.
- 20 My invention resides in the article, device, arrangement, method, and features of construction of the character hereinafter described and claimed.

For an understanding of my invention and for an illustration of some of the many forms thereof reference is to be had to the accompanying drawing, in which:

Figure 1 is an end view of a slit-forming device as constructed in accordance with my invention;

Fig. 2 is a side elevational view of the device shown in Fig. 1;

Fig. 3 is a plan view of the device shown in Fig. 1;

Fig. 4 is an end view of another form of slit-forming device as constructed in accordance with my invention;

Fig. 5 is a side elevational view of the device shown in Fig. 4; and

Fig. 6 is a plan view of the device shown in Fig. 5.

In general, my invention relates to slit-forming devices wherein the slit is traversed by a light beam which cooperates with a moving film to form a sound wave record thereon or wherein the light beam passes from a movable film to form a sound wave record thereon or wherein the light beam passes from a movable film in the reproduction of sound from a sound wave record previously

formed on the latter. Slits of this character are ordinarily relatively long as compared with their width, the width usually being small, as of the order of 0.1 to 0.05 mm., more or less. By my invention, the slit-forming device is of novel construction and is constructed in a novel manner to thereby eliminate various disadvantages of prior art devices.

Referring now to the form of my invention shown in Figs. 1, 2 and 3, A represents a plate or member of suitable sheet material having sections 1, 1a angularly related with respect to each other to any suitable degree. The plate A may exist as a relatively straight piece of material and may be bent into suitable angular formation in any suitable manner. Or, an angular member of the character desired may be produced in any other suitable manner.

Preferably, the aforesaid member A is of metallic character such, for example, as molybdenum or other metals of the same group which, while in sheet-like form and as generally stated above, may be suitably shaped or bent, while either hot or cold, to produce the disclosed angular member or one the equivalent thereof. The metal used may preferably be such as to withstand high temperatures, in the event it is desired to place the device within an enclosure or otherwise adjacent a source of illumination. Preferably, the interior surfaces of the angular sections 1, 1a meet at a sharply defined single straight line 2.

In accordance with my invention a section of the member A at the nose or angle-forming zone thereof is suitably removed, as by a grinding or milling operation, to produce a slit or passage 3 of a desired length and of suitable width. As will be understood, the extent to which the material is thus removed below the line 2 determines the initial width of the slit 3.

After a slit 3 of predetermined width has been produced as described above, the slit width may readily be increased or decreased by so moving the sections 1 and 1a that the angle formed thereby is either increased or decreased. If desired but by no means nec-

essarily, the slit width may be mechanically controlled by the provision of spaced screws 4 which extend loosely through the section 1 α , for example, and are threaded to the section 1. Obviously, these screws 4 may be suitably adjusted to either increase or decrease the width of the slit 3 and, when so adjusted, said screws 4 function to positively prevent change in the slot width. It shall be understood that 10 other equivalent arrangements may be utilized in lieu of the screws 4 for performing the function just stated.

Where the width of the slit is to be changed as described above, it may be desirable to 15 utilize a member A1 such as shown in Figs. 4, 5 and 6, the member A1 being more or less identical with the member A with the exception that the nose or angular zone thereof is formed or constituted by folded, side-by-side 20 sections 5, 5 α , Fig. 4. With such an arrangement, the surfaces limiting the slit are disposed well away from the joining section of the sections 1, 1 α and, therefore, alteration of the slit width may be easily and efficiently 25 effected.

With the form of my invention shown in Figs. 4, 5 and 6, it shall be understood that slit-controlling arrangements such as the screws 4, or equivalent, may be utilized if 30 desired.

In accordance with a preferred form of my invention the members A, A1, or equivalent, are one-piece sections of suitable sheet metal having sufficient thickness as to be inherently self-supporting. If desired, such sheet metal may be relatively non-elastic whereby the angular sections thereof are inherently capable of taking and retaining a set configuration. Due to this characteristic, 35 the angular sections readily remain in an adjusted position after adjustment thereof to obtain a desired slit width. If the sheet metal used is of a flexible and resilient nature, the device may be so formed that the 40 angle between sections 1 and 1 α is abnormally large, the screws as at 4 then being utilized to retain the sections 1 and 1 α at the exact angle necessary to provide a slit of the desired width.

50 As clearly appears from the drawing, the angular sections 1 and 1 α remain joined together beyond opposite ends of the slit. In other words, the aforesaid material-removing operation may be performed intermediate 55 the ends of the members A and A1. This is an advantageous feature resulting in the production of a slit-forming device wherein the angular sections determining the slit width are integral with each other beyond the ends 60 of the slit and, as a result, said slit width may readily be held constant or may be controlled in a desired manner.

The utilization of a one-piece member from 65 which the slit-forming device is formed is advantageous aside from the features above

pointed out. As regards those prior art arrangements wherein the slit is formed by the utilization of a plurality of plates, the one-piece device is a substantial improvement in that when the device is to be used in an 70 hermetically sealed chamber, the degasifying operation may more readily and more efficiently be performed therewith. Further, with those prior art arrangements wherein a straight metal plate is provided with a slit, 75 the slit width is dependent upon the thickness of the tools which are employed, it being extremely difficult to produce tools of the required degree of thinness and to obtain the desired slit after such tools have 80 been produced. Obviously with the angular section employed in accordance with my invention, no such difficulty arises or is presented.

While the invention has been described with respect to certain particular preferred examples which give satisfactory results, it will be understood by those skilled in the art after understanding the invention, that various changes and modifications may be made 85 without departing from the spirit and scope of the invention and it is intended therefore in the appended claims to cover all such changes and modifications.

What is claimed as new and desired to be 90 secured by Letters Patent is:

1. A light aperture forming device comprising a member having sheet-like sections integral with each other and of sufficient thickness to be inherently self-supporting, 100 said sections meeting at an angle and defining a slit to be traversed by a light beam, said sections being joined together beyond the ends of said slit.

2. A light aperture forming device comprising a member having sheet-like sections integral with each other and of sufficient thickness to be inherently self-supporting, 105 said sections meeting at an angle and defining a slit to be traversed by a light beam, said sections being joined together beyond the end 110 of said slit and being adjustable toward or from each other to vary the slit width.

3. A light aperture forming device comprising a member having sheet-like sections integral with each other and of sufficient thickness to be inherently self-supporting, 115 said sections meeting at an angle and defining a slit to be traversed by a light beam, and means for adjusting said sections relative to each other whereby the width of said slit may be changed.

4. A light aperture forming device comprising a molybdenum plate bent to form angularly related sections, the nose of said plate being cut away to form a slit extending lengthwise between said sections, said sections being adjustable toward or from each other to vary the width of said slit.

5. The method of producing a light aper- 130

ture slit-forming device, which comprises bending a sheet metal plate into angular formation, and removing material from said member in its angle-forming zone to form an 5 elongated slit therein.

6. The method of producing a light aperture slit-forming device, which comprises bending into angular formation a sheet metal plate inherently capable of retaining a set 10 formation, and removing material from said member in its angle-forming zone to form an elongated slit between the angular sections thereof.

7. A light aperture forming device comprising slit-forming members relatively movable angularly about a line along which said members meet for adjusting the width of the slit.

8. A light aperture forming device comprising a sheet of metal bent upon itself into contact centrally for a short distance and beyond extending divergently, portions of the nose and the adjacent diverging sections being cut away to produce a slit to be traversed 25 by a light beam.

In testimony whereof I have signed my name to this specification.

JOSEF ENGL.
